FLUE CLEANER

Apamenonadas S. Ketsios, Chicago, Ill.

Application February 20, 1939, Serial No. 257,308

3 Claims. (Cl. 15—104.14)

This invention relates to improvements in a device for cleaning or scraping the interior of pipes or other tubular bodies, and refers specifically to a device for cleaning or scraping flues by rotating the device in the interior of the flue, means being provided whereby the rotary scrapers bear against the walls of the tube or flue by spring pressure and pressure caused by centrifugal motion.

10 Rotary flue cleaners have heretofore been proposed wherein scrapers are mounted upon bowed leaf or blade springs, the principle employed residing in establishing radial pressure of the scrapers against the inner walls of the tube or flue by means of the springs upon which the scrapers are mounted, whereby rotation of the assembly causes the scrapers to remove soot or other deposits from the flue walls.

These prior art devices are of limited application, since the radial pressures of the blades against the flue walls for a predetermined bowing of the springs is constant and cannot be increased or decreased appreciably when cleaning a flue of predetermined diameter without removing the device from the flue and adjusting the bow of the springs, if the springs are adjustable. In addition, within working limits the ultimate radial pressure obtainable by means of springs is a limiting factor in itself. That is, for obvious reasons the thickness or weight of the springs cannot be too great if the device is to be readily handled or may, if used, be injurious to the flues.

In my invention moderate spring thickness or weight may be used, and the radial pressure is principally established, and may be varied by controlling the rate of rotation of the device, weights being carried by the springs to make centrifugal pressure a working factor in establishing radial pressure of the scrapers. In relying principally upon centrifugal force to establish radial pressure of the scrapers, a flexibility of control is obtained which is absent in prior art devices. For instance, where particularly stubborn deposits are encountered in the flue, the rotary speed of the scrapers may be increased and where in the same flue an area of flue wall is encountered having few, if any, deposits, the rotary speed of the scrapers may be diminished.

Other objects and advantages of my invention will be apparent from the accompanying drawing and following detailed description.

In the drawing, Fig. 1 is a side elevational view of my improved flue cleaner.

Fig. 2 is a top plan view of the device illustrated in Fig. 1.

Fig. 3 is a transverse sectional view taken on the line 3—3 of Fig. 1.

Fig. 4 is a fragmentary view of a modified form of spring attachment whereby the bow of the springs may be adjusted.

Referring in detail to the drawing, 1 indicates a rod which terminates at one end in a relatively enlarged square-sectioned head 2. Adjacent the opposite end of the rod a square-sectioned block 3 may be formed and adjacent thereto the rod 10 may be formed circular in section and may be provided with threads as indicated at 4 in Fig. 1. The rod 1, blocks 2 and 3 and the cylindrical threaded portion 4 may all be of integral construction.

5 A blade or leaf spring 5 may be rigidly anchored at one end by means of rivets 6 to each lateral face of the block 3. The springs 5 are bowed outwardly intermediate their length and toward their free ends they converge toward block 2. Block 2 carries a pair of transversely positioned pins 7 which extend at right angles to each other, said pins being rigidly positioned through block 2. Heads are provided at the ends of pins 7 and are adapted to confine the ends of springs 5 upon the pins 7, the springs being provided with longitudinal slots 9 through which the pins 7 extend. The heads 8 are spaced from the block 2 and therefore permit limited movement of the springs 5 toward and away from block 2.

Intermediate the length of each of the springs 5, scrapers 10 are carried, said scrapers comprising angle sections. One flange 11 of each of the angle sections is disposed flush with the surface of the spring upon which it is carried. The opposite flange 12 extends at right angles to the flange 11. The corners of the flange 12 are rounded or tapered as shown at 13 in Fig. 1. At the rear face of the intermediate portion of each of the springs 5, a weight 14 is carried, said weight being positioned upon the opposite face of the spring from the flange 11. The weight 14, flange 11, and spring 5 in each case, are rigidly joined by means of rivets or the like 15, which pass through flange 11, the intermediate portion of spring 5 and weight 14.

20 In utilizing the flue cleaner, the threaded end 4 of the rod 1 is engaged with a conventional flue cleaning rod (not shown). The cleaner is then inserted in a tube or flue (not shown), the head 50 or block 2 leading. Depending on the diameter of the tube or flue to be cleaned, the free ends of the springs 5, that is, the ends adjacent the pins 7, move inwardly along said pins toward block 2 thereby establishing a limited degree of pressure 55

- between the edges of the flanges 13 and the inner walls of the tube or flue to be cleaned. The opposite end of the flue cleaning rod may then be rotated, preferably by power, that is, an electric 5 motor or the like. This is conventional practice in the cleaning of flues. It can readily be seen that, the flanges 13 will thus scrape the interior surfaces of the tube or flue, tending to remove soot or other deposits from the flue walls.
- 10 If a particularly stubborn deposit is encountered, the speed of rotation of the flue cleaning rod is increased and in so doing the centrifugal force, made a workable factor by the presence of the weights 14, increases the radial pressure 15 with which the flanges 13 bear upon the inner walls of the flue. This relatively high speed of rotation may be maintained until the deposit in question is removed. As the cleaner continues its progress through the tube, portions of said 20 tube may be encountered which carry little or no deposits. At these points the speed of rotation of the cleaner may be reduced until the weights 14 have little influence upon the radial pressure of the flanges 13 upon the tube walls.
- 25 At these points it is entirely possible that the springs 5 are the principal factors in establishing the radial pressure.
- By providing a limited degree of lateral motion of the free ends of the springs 5 adjacent the 30 head 2, a cleaner of predetermined size may be adaptable for use in tubes or flues of a relatively wide range of diameters. In addition, when the ends of the springs 5 are in contact with the heads 8, the slots 9 permit an additional bowing 35 of the springs which will be caused by the centrifugal force established by the whirling weights 14. This factor permits the enlargement of the range of tube diameter within which the cleaner may be used.
- 40 In the rotating of the cleaner the flanges 13 move in a direction at right angles to their length and, consequently, tend to twist the springs 5. This twisting movement is normally greatest at the central portion of the springs. The 45 weights 14 in addition to functioning as pressure-producing agents, also function as reinforcing members which tend to resist the torsional effect and tend to distribute the torsional forces at both ends of the springs 5.
- 50 The absolute weight of the weights 14 will depend upon many factors including the character of the springs, that is, their thickness and temper and also will be determined by the speeds of rotation which are capable of being produced 55 by the driving medium. In addition, the absolute weight of the weights 14 will be determined by the sizes of the pipes wherein the cleaner is to be used, the larger the pipes the larger the weights since the larger pipes are capable of with- 60 standing greater radial pressures.
- Referring particularly to Fig. 4, a slight modification of my invention is shown wherein rod 16, corresponding to rod 1 in Fig. 1, is formed with a relatively enlarged square-sectioned portion 65 17 adjacent its end. The rod 16 beyond the square-sectioned portion 17 is threaded as indicated at 18 to engage with an internally threaded adjusting nut 19. A square-sectioned sleeve 20 is slidably positioned upon the portion 17 and 70 an end thereof normally bears against nut 19. The sleeve 20 carries a spring 21 on each of its faces, said springs being secured thereto by means of screws or the like 22. The springs 21 for the remaining distance are similar to springs 5, carrying scrapers 10, weights 14, and the same may

be anchored upon a block similar to the block 2 in the manner hereinbefore described.

In utilizing this form of my invention it can readily be seen that the bow of the springs 21 may be adjusted by means of the nut 19 to increase or decrease the degree of bowing. By this provision the flexibility of use of the cleaner is extended.

It is not essential that the rod 1 extend between the square-sectioned block 3 and the head 10 2. However, the provision of the intermediate rod makes the structure stronger and prevents undue twisting of the springs. Both constructions, however, are broadly contemplated by my invention.

I claim as my invention:

1. A flue cleaner comprising a supporting member adapted for engagement at one end with a flue cleaner rod, a plurality of relatively elongated blade springs each of which is anchored at one end in a circumferentially spaced manner by said supporting member and engaged for limited longitudinal and lateral movement at the opposed end, the longitudinal axes of said springs being disposed generally in a direction parallel to the axis of said supporting member, said blade springs being bowed outwardly intermediate their length in radial directions from said supporting member, a longitudinally extending scraper carried on the outer face of an intermediate portion of each of said blade springs, and a weight carried by an intermediate portion of each of said blade springs substantially coextensive with the length of said scrapers whereby rotary motion of said supporting member exerts 35 centrifugal force upon said weights to force said scrapers outwardly against the interior of a flue.

2. A flue cleaner comprising a supporting rod adapted for engagement at one end with a flue cleaner rod, a plurality of relatively elongated 40 blade springs each of which is carried at one end upon said supporting rod adjacent its end, the longitudinal axes of said springs being disposed generally in a direction parallel to the axis of said supporting rod, said blade springs being 45 bowed outwardly intermediate their length in radial directions from said supporting rod, a plurality of transverse pins carried near the opposite end portion of said supporting rod, the opposite ends of said blade springs being loosely 50 secured to said pins and adapted to limited longitudinal and lateral end movement, a scraper carried on the outer face of an intermediate portion of each of said blade springs, said blade springs being weighted intermediate their lengths 55 and substantially coextensive of said scrapers to exert substantially uniform radial pressure of said scrapers upon the inner face of a flue when said supporting rod is rotated.

3. A flue cleaner comprising a supporting rod adapted for engagement at one end with a flue cleaner rod, a sleeve slidably but non-rotatably carried on said rod, a plurality of relatively elongated blade springs each of which is anchored at one end upon said sleeve, the longitudinal axes of said springs being disposed generally in a direction parallel to the axis of said supporting rod, said blade springs being bowed outwardly intermediate their length in radial directions from said supporting rod, a plurality of transverse pins carried by the opposite portion of said supporting rod, the opposite ends of said blade springs being loosely carried on said pins, in such manner that said ends have limited longitudinal and transverse freedom of movement 75

with respect to said pins, a longitudinally extending scraper carried on the outer face of an intermediate portion of each of said blade springs, said blade springs being weighted intermediate
5 their lengths substantially coextensive with said scrapers to exert radial pressure of said scrapers

upon the inner face of a flue when said supporting rod is rotated, and means for moving said sleeve longitudinally along said supporting rod to adjust the bow of said blade springs.
